(Cl. D90—20)

Figure 1 is a front view of the tired wheel unit showing my new design;

Figure 2 is a side elevational view, the other side being substantially plain; and

Figure 3 is an enlarged sectional view taken on the line 3—3 through the center of Figure 2.

The hatching in the drawing, Figures 1 and 2, indicates contrasting colors. The dominant features of the design reside in the portions shown in full lines.
